CLAIM

The ornamental design for a support for a purse, as shown and described.

DESCRIPTION

FIG. 1 is a top plan view of a support for a purse showing my new design in an opened position.

FIG. 2 is a top plan view of the support for a purse in a closed position.

FIG. 3 is a perspective view of the support for a purse in the opened position, as viewed from the upper right of FIG. 1. FIG. 4 is a bottom plan view of the support for a purse in the opened position, wherein the view is rotated 90 degrees counter-clockwise from the orientation of FIG. 1.

FIG. 5 is a right side elevation view of the support for a purse in the opened position.

FIG. 6 is a left side elevation view of the support for a purse in the opened position.

FIG. 7 is a lower end elevation view of the support for a purse in the opened position.

FIG. 8 is an upper end elevation view of the support for a purse in the opened position; and,

FIG. 9 is a bottom plan view of the support for a purse in the closed position.

The elements shown in broken lines depict portions of the support for a purse that form no part of the claimed design. Lightly weighted lines are shading lines which illustrate contour.
